UNITED STATES PATENT OFFICE.

KOLMAN EMMERMAN AND WILLIAM NATHANSON, OF CHICAGO, ILLINOIS.

RADIATOR.

1,313,077.

Specification of Letters Patent. Patented Aug. 12, 1919.

Application filed April 20, 1916. Serial No. 92,407.

To all whom it may concern:

Be it known that we, KOLMAN EMMERMAN and WILLIAM NATHANSON, citizens of the United States, and residents of the city of Chicago, county of Cook, and State of Illinois, have jointly invented certain new and useful Improvements in Radiators, of which the following is a specification.

Our invention relates to improvements in radiators designed for use especially in connection with automobiles for cooling the water which is circulated through the cooling jackets of the cylinders of the automobile engine.

15 The object of our invention is the production of a radiator of the character mentioned which will be of durable and economical construction and which will be capable of efficient service in the cooling of water 20 passed therethrough.

Other objects will appear hereinafter.

The invention consists in the combinations and arrangements of parts hereinafter described and claimed.

25 The invention will be best understood by reference to the accompanying drawing forming a part of this specification, and in which,

Figure 1 is a front elevation of an automobile radiator embodying the invention,

30 Fig. 2 is a front elevation of a fragment of the radiator, enlarged,

Fig. 3 is an enlarged vertical transverse section of a fragment of the radiator, and

35 Figs. 4 and 5 are sections taken on lines $x-x$ and $y-y$ respectively of Fig. 3.

The preferred form of construction, as illustrated in the drawing, comprises a radiator frame 1 which is of conventional construction, being provided in its upper end with the usual receiving chamber and at its lower end with the usual dispensing chamber.

40 Mounted in the central opening in frame 1 is the radiator body 2 which establishes communication between the receiving and dispensing chambers of the radiator frame as is generally understood. Said radiator body is formed of a series of vertically extending units arranged side by side, each of said units consisting of two strips 3 of sheet metal or other heat conducting material. Each of the strips 3 is formed with alternating transversely extending straight flat por-

tions 4 and inwardly offset portions 5. Each of the portions 5 is formed centrally with an outwardly depressed portion 6. The portions 4 of one strip register with the portions 5 of the other, the longitudinal edges of said strips interlocking with and snugly fitting each other, as clearly shown in Fig. 2, said edges being sealed together by dipping the same in solder, as is the usual practice. With this arrangement, it will be seen, that a tortuous passage 7 will be formed between the strips 3 in each unit which serves, in the operation of the radiator, to somewhat retard the flow of the water therethrough in order to effect thorough cooling of the same by the time the water has passed completely through the radiator. Also, the peculiar formation of the strips 3 and particularly the provision of a depression or concavity in each of the inwardly offset portions 5, serves to lend strength and rigidity to the device, and therefore, to adapt the same to stand up under the rough treatment to which the same is subjected when in use.

45 Certain of the straight flat portions 4 of the strips 3 of each unit are formed with outwardly extending plaits 8 in which are formed blind passages which communicate with the corresponding passage 7. The plaits 8 of one unit engage with the straight flat portions 4 of the adjacent unit, and thus serve as a means of spacing the units apart so as to form transversely extending air passages 9 between the same. The central portions of the plaits 8 of said plaits are depressed or offset inwardly as at 8' so that 50 said plaits engage with the portions 4 only at the ends of said plaits, as clearly shown in Fig. 4. This results in spaces being formed between the central portions of the plaits 8 of said plaits and the adjacent flat portions 4 which results in the production of a maximum of heat radiating surface which, of course, is of prime importance in a radiator. These spaces which are formed at the ends of the plaits 8 also result in the formation of 55 vertical air passages which intersect the horizontal passages for the air, such as are constituted by the openings 9. The units are all connected together to form one solid body in the dipping of the longitudinal edges thereof in solder, as above described.

60 All of the strips are of identical form, being pressed or stamped from the same die,

the radiator being built or assembled by matching the strips together in the manner above set forth.

While we have illustrated and described 5 the preferred form of construction for carrying our invention into effect, this is capable of variation and modification without departing from the spirit of the invention. We, therefore, do not wish to be limited 10 to the precise details of construction set forth, but desire to avail ourselves of such variations and modifications as come within the scope of the appended claims.

Having described our invention what we 15 claim as new and desire to secure by Letters Patent is:

1. A radiator comprising a series of vertically disposed units each consisting of a pair of strips of heat conducting material 20 arranged side by side, each of said strips having alternating transversely extending straight flat portions and inwardly offset portions, the central portion of each of said offset portions being pressed outwardly, the 25 straight flat portions of one strip registering with the offset portions of the other, and the longitudinal edges of said strips interlocking with and snugly fitting each other forming a tortuous vertically extending wa- 30 ter passage between said strips; and outwardly extending plaits on said strips at certain of the straight flat portions thereof having blind passages formed therein com- 35 municating with the corresponding vertical passage, the bights of the plaits of one unit

engaging against the unplated straight flat portions of adjoining strips to space adjacent units apart, substantially as described.

2. A radiator comprising a series of vertically disposed units each consisting of a pair of strips of heat conducting material arranged side by side, each of said strips having alternate straight flat portions and inwardly offset concave portions, the straight flat portions of one strip registering with the offset portions of the other and the longitudinal edges of said strips interlocking with and snugly fitting each other forming a tortuous vertically extending wa- 45 ter passage between said strips; and outwardly extending plaits on said strips having blind passages formed therein communicating with the corresponding vertical passage, the bights of the plaits of each unit engaging against the straight flat portions 50 of adjacent units to space the same apart, the central portions of the bights of said plaits being inwardly offset to afford spaces between said central portions of the bights 55 of said plaits and the adjacent surfaces of adjacent units, substantially as described.

In testimony whereof we have signed our names to this specification in the presence of two subscribing witnesses.

KOLMAN EMMERMAN.
WILLIAM NATHANSON.
